(57) **CLAIM**

The ornamental design for an aromatherapy machine, as shown and described.

DESCRIPTION

FIG. 1 is a right, top perspective view of an aromatherapy machine, showing my new design;

FIG. 2 is a left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof.

FIG. 9 is an enlarged view of detail 9 in FIG. 1;

FIG. 10 is an enlarged view of detail 10 in FIG. 3;

FIG. 11 is an enlarged view of detail 11 in FIG. 4;

FIG. 12 is an enlarged view of detail 12 in FIG. 5;

FIG. 13 is a right, top reference view of the aromatherapy machine, indicating the first usage environment;

FIG. 14 is a left, bottom reference view of the aromatherapy machine, indicating the first usage environment;

FIG. 15 is a front elevational view of the aromatherapy machine, indicating the first usage environment;

FIG. 16 is a right, top reference view of the aromatherapy machine, indicating the second usage environment;

FIG. 17 is a left, bottom reference view of the aromatherapy machine, indicating the second usage environment; and,

FIG. 18 is a front elevational view of the aromatherapy machine, indicating the second usage environment.

The dashed broken lines in the figures are for the purposes of illustrating portions of the aromatherapy machine that form no part of the claimed design.

The short-short-long dashed broken lines immediately adjacent to the claim area in the FIG. 1, FIG. 2, FIG. 7, FIG. 8 are for the purposes of illustrating the boundaries of the aromatherapy machine, and form no part of the claimed design.

The dash-dot-dash broken lines are for notating enlarged views and form no part of the claimed design.

The dashed broken lines in the FIG. 13 to FIG. 18 are for the purposes of indicating the usage environment of the aromatherapy machine and form no part of the claimed design.

1 Claim, 16 Drawing Sheets
